FRANZ G. SIEMERS, OF WINONA, MINNESOTA.

Letters Patent No. 86,783, dated February 9, 1869.

IMPROVED MEAT-CHOPPER.

The Schedule referred to in these Letters Patent and making part of the same.

To all whom it may concern:

Be it known that I, FRANZ G. SIEMERS, of Winona, in the county of Winona, and State of Minnesota, have invented certain new and useful Improvements in Mounting the "Meat-Blocks" of Meat-Choppers; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use said invention, I will proceed to describe it.

Figure 1 is a longitudinal vertical section through the centre of the block on the line *x* of fig. 2, and

Figure 2 is a vertical cross-section on the line *y* of fig. 1.

My invention relates to certain improvements on the meat-cutting machine for which Letters Patent were granted to me, bearing date August 25, 1868, and numbered 81,421, and consists in an improved method of mounting or supporting the chopping or meat-block.

The device consists of a rectangular sliding frame, mounted on the table or platform underneath the chopping-block, which frame, when pushed back, brings the block in the proper position below the cutting-knives, and, when drawn forward, brings the block out from under the knives in such a position that the meat can be readily examined or removed, an operation which, in my previous machine, was quite troublesome, on account of the interference of the knives; and also, in combination with the said sliding frame, of an adjustable pivot, on which the block turns during the operation of chopping.

A represents the bed or platform of the machine, having secured to its upper side four standards, *G*, which are placed, two in front and two in the rear of the main shaft *D*, and arranged, in relation to one another, as the four corners of a rectangle.

The two rear standards are higher than the others, and have openings through their upper ends, in a direction running lengthwise of the machine; and the front standards have slots cut into them from the top, a short distance downward, and running in the same direction as the openings in the rear standards.

On these standards I mount the metal frame *F*, composed of the two side rails or bars *i*, connected at their ends by the rods *e*, as shown, the side bars of the frame sliding in the openings in the standards before mentioned.

This frame *F* is greater in length than the distance between the standards, and may be slid back and forth thereon.

The pivot or standard *C*, upon which the block rotates, is made adjustable vertically, and is furcated, and sits astride of the main shaft *D*, as shown in fig. 1, and passing down through the platform *A*, and being con-

nected to the inner end of a lever, *E*, pivoted to the frame of the machine at *a*, the other end of which projects out on one side of the machine, as shown in fig. 2, so that by forcing down the outer end of the lever, the pivot *C* is elevated, and *vice versa*.

The chopping-block or tub, during the operation of the machine, is supported by friction-rollers, the same as in my previous machine. The pivot *C* is elevated, so as to enter the hole in the centre of the block, as shown in red lines in fig. 2.

On the lower edges of the side bars of the frame *F* are cut inclines, *d*, in such positions that when the frame is at the end of its backward movement, the standards *G* will enter them, and thus allow the whole frame *F* to fall a distance equal to the depth of the inclines.

On the upper edges of the said side rails of the frame are four points or lugs *b*, which bear or catch against an annular flange on the bottom of the block; (which in this is the inner edge of the ring or plate *f*, on the outer edge of which are cut the ratchet-teeth by which the block is rotated,) and thus, when the frame is moved, it moves the block with it.

When the device is to be operated, the frame is drawn out forward, and the chopping-block placed upon it in such a position that the lugs *b* shall be inside of the flange or plate. The frame is then pushed back, carrying the block with it over the friction-rollers, and the hole in the bottom over the pivot *C*, at which point the inclines *d* will have reached the standards *G*, and the frame *F* will drop down clear from the block and leave it resting upon the rollers. The pivot *C* is then elevated, and the machine is ready for operation.

The points or lugs *b* always guide the block, so that the hole in its under side shall stand directly over the pivot *C*, so that when elevated it will readily enter.

When the block is to be drawn out, the above operations are reversed, *i. e.*, the pivot *C* depressed and the frame drawn forward, when it will rise, and the points *b*, engaging with the block, bring it out forward from under the knives.

If desired, any suitable devices may be provided for securing the lever *E* up or down.

Having thus described my invention,

What I claim, is—

1. The sliding frame or bars, provided with the inclines, and arranged to slide to and fro on its supports *G*, in combination with a meat-chopping machine, substantially as and for the purpose set forth.

2. The combination of the adjustable pivot *C* and sliding frame *F*, when arranged to operate as herein described.

FRANZ G. SIEMERS.
